UNITED STATES PATENT OFFICE.

JOSEPH BREN, OF OGEMA, MINNESOTA.

DESIGN FOR A GREASING IMPLEMENT.

Application filed February 28, 1924. Serial No. 8,776. Term of patent 7 years.

To all whom it may concern:

Be it known that I, JOSEPH BREN, a citizen of Czechoslovakia, residing at Ogema, in the county of Becker and State of Minnesota, have invented a new, original, and ornamental Design for Greasing Implement, of which the following is a specification, reference being had to the accompanying drawing, forming part thereof.

The figure is a view in perspective of a greasing implement, showing my new design.

I claim:

The ornamental design for a greasing implement, as shown.

JOSEPH BREN.
